UNITED STATES PATENT OFFICE.

WILLIAM H. EMERICK, OF OMAHA, NEBRASKA.

HATCHWAY-OPENING FOR REFRIGERATOR-CARS.

1,220,830.

Specification of Letters Patent. Patented Mar. 27, 1917.

Application filed October 15, 1915. Serial No. 56,132.

To all whom it may concern:

Be it known that I, WILLIAM H. EMERICK, a citizen of the United States, residing at Omaha, in the county of Douglas and State of Nebraska, have invented certain new and useful Improvements in Hatchway-Openings for Refrigerator-Cars, of which the following is a specification.

This invention relates to the construction of hatchway openings for refrigerator cars, and has for its primary object to provide hatches on opposite sides of the middle line of the car and in communication with the ice-box at the end thereof, which hatches have their inner walls deflected toward the middle of the car so as to provide a downwardly flaring or enlarging opening, that not only facilitates chopping in the ice and distributing it toward the intermediate portion of the ice-box, but affords a freer escape for a rising column of warm air when the car is traveling under ventilation, than would be the case if the sides of the hatch descended in substantially vertical lines or 25 with the tapering walls continued as heretofore.

A further object of the invention is to provide a very effective, though inexpensive way of obtaining the form of hatch above described, namely, by constructing headers which provide transverse walls on the hatch with reentrant cuts at their inner ends which receive the vertical and inclined portions of the inner longitudinal headers, and by placing a brace-block in between these inner longitudinal headers so as to firmly sustain the latter against not only the wedging action of the inner insulating plug or cover, but also against the wedging action of ice 40 that is being forced through the hatch.

A further object is to provide hatchway openings as above described, which, while especially adapted for refrigerator cars, are also applicable to floating cargo carriers or 45 the like.

Further features of the invention will be more fully understood upon reference to the accompanying drawings which form part of this specification.

50 In said drawings:—

Figure 1 is a plan view partly in section of a portion of a refrigerator car showing the application of the hatch doors constructed in accordance with the present invention;

Fig. 2 is a longitudinal section of a portion of a refrigerator car illustrating the application of the invention;

Fig. 3 is a cross section of a portion of a refrigerator car illustrating the application of the present invention;

Fig. 4 is a longitudinal section on the line 4—4 of Fig. 1.

Referring to the drawings in detail, A represents a refrigerator car which may be 65 constructed of conventional design embodying the usual ventilating system, and a represents the hatches, which, in accordance with the present invention, are provided on opposite sides of the running board B of the 70 car, and in communication with the ice-box at the end thereof. And these hatches a embody in their construction, inner walls b which are deflected toward the middle of the 75 car to provide a downwardly flaring or enlarging opening which not only facilitates the chopping in the ice and distributing it toward the intermediate portion of the ice-box, but affords a freer escape for a rising column of warm air when the car is traveling under ventilation. These downwardly flaring inner walls are provided by constructing headers 1 which provide transverse walls on the hatch with reentrant cuts 2 at their inner ends, which receive the inner longitudinal headers 3 and 4 respectively, and by placing a brace block 5 in between these longitudinal headers 3 and 4 so as to firmly sustain the latter against not only the wedging action of the inner insulating 80 plug or cover C, but also against the wedging action of the ice that is being forced through the hatch. The longitudinal headers 3 and 6 and the transverse headers 1 slope downwardly and inwardly to provide 85 a tapering seat for the plug or cover C. Both the transverse and longitudinal headers of the hatches are preferably covered with a metallic sheathing such as 7. It is 90 to be noted that the brace blocks 5 are constructed at their ends, with inclined portions which conform to the inclined portions of the inner longitudinal headers, and in this manner firmly sustain the inner longitudinal headers against displacement.

I claim:—

1. In a railway refrigerator car, the combination of a roof provided with a hatch opening, a frame surrounding said opening and forming the walls thereof, one of said 110

walls having its lower portion sloping downwardly and outwardly relative to its upper portion to permit access to the space beneath said roof at the side of said opening.

2. In a railway refrigerator car, the combination of a roof provided with a hatch opening, a plug or cover therefor, a frame surrounding said opening and forming the walls thereof, three of said walls sloping downwardly and inwardly and the other wall having its upper portion sloping downwardly and inwardly to form a seat for said plug or cover, the lower portion of said last named wall sloping downwardly and outwardly to permit access to the space beneath said roof at the side of said opening.

3. In a railway refrigerator car, the combination of a roof provided with a running board and oppositely disposed hatch openings in the roof at the sides of said running board, a frame surrounding each opening

and forming the walls thereof, the inner walls of said frames having portions thereof sloping downwardly and toward each other to permit access through said openings to the space beneath said running board.

4. In a railway refrigerator car, the combination of a roof provided with a running board and oppositely disposed hatch openings in the roof at the sides of said running board, a frame surrounding each opening and forming the walls thereof, the inner walls of said frames having portions thereof sloping downwardly and toward each other to permit access through said openings to the space beneath said running board, and a brace block located beneath the running board and between the inner walls of said openings.

The foregoing specification signed at Omaha, Nebraska, this 24th day of September, 1915.

WILLIAM H. EMERICK.

Copies of this patent may be obtained for five cents each, by addressing the "Commissioner of Patents Washington, D. C."
